UNITED STATES PATENT OFFICE

JAMES C. TRAVILLA, JR., OF UNIVERSITY CITY, MISSOURI, ASSIGNOR TO GENERAL STEEL CASTINGS CORPORATION, OF GRANITE CITY, ILLINOIS, A CORPORATION OF DELAWARE

RAILWAY ROLLING STOCK CONSTRUCTION

Application filed December 26, 1929. Serial No. 416,628.

My invention relates to railway rolling stock and consists in a novel spring equalizing system for supporting a vehicle frame from vehicle axles and in novel frame and journal box structure particularly adapted for the system.

I have developed my arrangement particularly for use in the spring equalizing system of a locomotive.

10 It has been the common practice in such structures to mount journal boxes on the driver axles, mount leaf springs on top of the journal boxes, suspend links from the adjacent ends of the springs and support equalizers therefrom, connecting the ends of the equalizers to the lower ends of the links and pivoting the intermediate portion of the equalizers on the locomotive frame.

This arrangement requires the upper portion of the locomotive frame above the pedestal openings to be constructed so as to accommodate the spring saddles and the equalizer suspending links; and locates the springs either above the side members of the frame or, if the side members are hollow, between the vertical walls of the side members, the side members of the latter type having large openings in the top for insertion of the spring. This construction, therefore, makes it very difficult, in view of the necessary clearance conditions for the various parts of spring rigging and underframe, to obtain the desired cross sectional area and contour of side frame members above the pedestal openings.

The main objects of my invention are to locate the springs below the main side members of the frame and to eliminate provision for the accommodation of spring saddles and links in the frame member as referred to, and also to permit the springs and hangers to be easily removable and to eliminate the possibility of hangers cutting into the walls of the underframe.

Another object of my invention is to reduce the number of parts of the spring equalizing system and simplify the construction by utilizing the journal boxes themselves as equalizer elements of the spring system.

Another object of my invention is to pro-

vide the journal box with thimbles at the bottom of the box to increase the strength and act as spacers and prevent the box from closing in and binding the cellars.

Another object of my invention is to pivot the journal boxes on the axles, thereby eliminating much of the binding action which results from the vertical movement of boxes in their pedestals in the ordinary equalizing systems in which the boxes have sliding movement only.

Another object of my invention is to eliminate pedestal binders so as to facilitate the application and removal of boxes, springs and drivers; and to eliminate the machining of the pedestal binders and toes.

A further object of my invention is to simplify, and thereby improve the appearance, increase the strength and, at the same time, lighten and otherwise improve the frame structure which is made possible by providing for better distribution of the metal as a result of the elimination of provision for passage therethrough of the springs, spring saddle, and equalizer supporting links.

These and other objects of my invention are attained in the structure illustrated in the accompanying drawings, in which—

Figure 1 is a top view of one longitudinal half of a locomotive frame arranged for my novel construction.

Figure 2 is a side elevation of the same showing the equalizing system for supporting the frame on the driving axles.

Figure 3 is an enlarged section, taken on the line 3—3 of Figure 1, detailing the construction of box and pedestal, etc.

Figure 4 is a horizontal section taken on the line 4—4 of Figure 3.

Figure 5 is a vertical section taken on the line 5—5 of Figure 3.

A series of four drivers 1, 2, 3, 4 is shown, each driver being mounted upon a corresponding axle 5, 6, 7, 8, respectively, and each axle mounting a journal box 9 which rests upon the usual brass 10 carried by the axle and is arranged to tilt about the axle as will be detailed later.

Each box includes projecting flanges or arms 11 from which links 12 are suspended.

and the links on the adjacent flanges of two adjacent boxes pivotally mount the ends of leaf springs 13. The right hand end of the main system comprising the outer flange 11a of the box on axle 8 is anchored to the frame by means of a short link 14 and the left hand end of the main system supports the end of an equalizer 15 which preferably is fulcrumed on the truck frame (not shown) and is connected to the truck spring system (not shown) in the usual manner.

The main frame 17 includes a side member 18 having a general box-like cross section and including pedestal jaws 19 and depending elements 20 between said jaws resting on the springs 13. Preferably, the pedestal jaws and elements 20 are formed integrally with the side member 18, the entire frame structure consisting of a one-piece casting, although this preferred construction is not essential to the embodiment of my invention. In comparison with previous constructions, the side members of my underframe have a greater depth and uniformity of section at the portions above the pedestal openings and therefore it is easier to obtain the necessary strength; and the radii at the top corners of the pedestal openings are larger so as to provide greater strength and easier machining of the pedestals. This construction is particularly advantageous for three or four cylinder locomotives in which the center crank and piston rod necessitate the elimination of the desirable framing intermediate the side frames which is possible with a two cylinder locomotive.

The box and container bearing structure differs substantially in a number of respects from the usual driving box structure. The semi-circular brass 10 is applied to each axle in the usual manner. The box structure receiving this brass includes front and rear walls 22 and 23, respectively, the longitudinal extensions of which form the flanges or arms 11 previously referred to. A cylindrical transverse wall 24 extends between walls 22 and 23. Blocks or sleeves 25, preferably of brass, are applied to this portion of the box and have concave inner surfaces fitting the exterior surface of the steel box and have straight outer surfaces engaging the pedestal jaws 19 or, preferably, hardened steel liners 26 fitted over the pedestal jaws and secured thereto by bolts 28. This arrangement of brass against steel reduces the wear on the surfaces of adjacent parts. Transverse bolts 21 extend through the pedestal jaws and through elongated vertical slots 27 in the box flanges 11 and serve to hold the boxes in the pedestals when the structure is being assembled or disassembled, and to hold the box in place if the engine is to be lifted. The lower portions of the walls 22 and 23 on opposite sides of the axles are securely braced by spacers or thimbles 29 and bolts 30 extending

through the same and the box walls. These thimbles comprise compression members for body of the box and support grease cellar C.

This construction provides a box which may tilt about the axle to the extent necessary to accommodate variation in the flexing of the springs and to effect desired distribution of the load. At the same time, the axle, box and sleeve may move up and down vertically in the pedestal openings in the usual manner. The construction avoids the condition existing in the ordinary box with parallel sides and rigid bearing support in which the box, as a whole, tends to tilt on the axle and stick in the pedestal and the overcoming of which tendency results in undue and uneven wear on the sides of the box.

It will be readily seen that the replacement of a spring or a box, or an axle or an axle bearing, is effected much more readily than in the ordinary construction where the springs and spring hangers are contained in part or in whole in the locomotive frame and are covered in whole or in part by valve gearing or brackets, pumps, etc., mounted on the frame. The points of support of the frame are very low which provides increased stability. The frame construction is strengthened (or equal strength can be obtained with less material) because of the elimination of the openings in the frame previously necessary to accommodate the spring rigging and a substantial amount of machining on the frame is eliminated.

Obviously the pattern work for a cast bed is simplified and other molding operations facilitated.

Obviously other variations may be made in my structure without departing from the spirit of my invention and I contemplate the exclusive use of such modifications as come within the scope of my claims.

I claim:

1. In combination, a railway vehicle frame including main side members, a wheeled axle, and a spring equalizing system for supporting said frame on said axle including a journal box carried on said axle and forming an element in said system.

2. In combination, a railway vehicle frame, a wheeled axle, a journal box tiltingly mounted on said axle, springs at opposite sides of said box each having an end secured to the adjacent side of said box, and means holding the opposite ends of said springs, the intermediate portions of said springs supporting said frame.

3. In a railway vehicle, a frame, a plurality of axles, journal boxes carried by said axles and having a main body portion arranged to tilt thereon in a plane extending longitudinally of said frame, a series of springs arranged longitudinally of the frame in an equalizing system in which the extreme ends of the system support said

- frame, the intermediate portion of each spring supporting said frame, and the ends of said springs intermediate the ends of the system being suspended from said journal boxes.
4. In a railway vehicle, a plurality of wheeled axles, journal boxes tiltingly mounted on said axles, springs extending between said boxes with their ends pivotally connected to said boxes, and a vehicle frame supported on said springs intermediate their ends.
5. In a railway vehicle, spaced axles, individual journal boxes tiltingly mounted thereon, links suspended from the adjacent sides of said boxes, a leaf spring having its ends carried by said links, and a frame element supported on the intermediate portion of said spring.
6. In a railway vehicle, spaced axles, individual journal boxes tiltingly mounted thereon, links suspended from the adjacent sides of said boxes, a leaf spring having its ends carried by said links, and a frame element supported on the intermediate portion of said spring, said spring being located below the level of said axles.
7. In a railway locomotive, spaced axles, journal boxes thereon, springs extending between said boxes below the level of said axles, individual connections between the ends of said springs and the sides of the adjacent boxes whereby said boxes form parts of the spring equalizing system, and a side frame extending over said boxes and having its bottom portion mounted on said springs.
8. In a railway locomotive, spaced axles, journal boxes thereon, springs extending between said boxes below said axles, individual connections between the ends of said springs and the sides of the adjacent boxes whereby said boxes form parts of the spring equalizing system, and a side frame extending over said boxes and having pedestals for receiving said boxes and having its bottom portions between said pedestals mounted on said springs.
9. In a railway locomotive, spaced axles, journal boxes thereon, springs extending between said boxes with their ends connected to the adjacent sides of said boxes, said springs being below the level of the tops of said boxes, said boxes and springs forming a continuous equalizing system from axle to axle, and a side frame member of box-like cross section from end to end extending over said boxes and springs and slidably receiving said boxes and supported by said springs.
10. In a railway vehicle, a frame with depending pedestal jaws, axle box elements slidably on said pedestal jaws, a box body journalled in said elements to rotate about the box axis, and spaced arms on each side of said body portion straddling the corresponding pedestal jaw and projecting from the box beyond the jaw to provide support for a spring beneath said frame.
11. In a railway vehicle, an axle, a frame having spaced pedestal jaws, and an axle box including a vertically slidable portion and a cylindrical portion pivotally supported on said slidable portion and having arms extending laterally from said box alongside of said pedestal jaws.
12. In a railway vehicle, an axle, a frame having spaced pedestal jaws, and an axle box including a cylindrical body portion supported on said axle and having arms extending laterally from said box alongside of said pedestal jaws, there being a sliding element journalled on said body portion and having straight outer surfaces slidably engaging the opposed faces of said pedestal jaws.
13. In a railway vehicle, an axle, a frame having spaced pedestal jaws, and an axle box including a cylindrical body portion supported on said axle and having arms extending laterally from said box alongside of said pedestal jaws, said pedestal jaws having vertically extending slots opening transversely of the frame, and bolts through said arms and said slots for maintaining the assembly of said box and frame.
14. In an equalizer system for a railway vehicle, springs spaced longitudinally of the vehicle, an equalizer comprising two transversely spaced longitudinally extending members each secured at its ends to said springs, said members being connected by the main body portion of a journal box at the fulcrum point of the equalizer.
15. In an equalizer system for a railway vehicle, an equalizer comprising two spaced longitudinally extending members connected by the main body portion of a journal box at the fulcrum point of the equalizer, said journal box having a cylindrical contour on the outside between said members and there being an opening on its underside for accommodation of an axle journal, and spacers in vertical alignment with said members at the lower portion of said opening.
16. In an equalizer system for a railway vehicle, an equalizer comprising two spaced longitudinally extending members connected by the main body portion of a journal box at the fulcrum point of the equalizer, said journal box having a cylindrical contour on the outside between said members and there being an opening on its underside for accommodation of an axle journal, spacers in vertical alignment with said members at the lower portion of said opening, and a pair of shoes having a concave surface engaging the cylindrical surface of said body portion, said shoes having flat surfaces for slidably engaging the surfaces of pedestal legs.
17. In an equalizer system for a railway vehicle, an equalizer comprising two spaced longitudinally extending members connected by the main body portion of a journal box at the fulcrum point of the equalizer, said

journal box having a cylindrical contour on the outside between said members and there being an opening on its underside for accommodation of an axle journal, and spacers in vertical alignment with said members at the lower portion of said opening, there being sufficient space between the top of said spacers and the axle journal to mount a grease cellar above said spacers.

18. In combination, a railway vehicle frame, spaced axles having wheels mounted thereon, a combined equalizer and journal box mounted on each axle, a spring located between said axles and substantially in alignment with said combined equalizer and box, said spring having its ends secured to the adjacent portions of adjacent equalizers, the intermediate portion of said spring supporting said frame, said combined journal box and equalizer and said spring comprising elements of an equalizing system.

19. In a railway vehicle, a frame, a plurality of axles, an equalizing system including journal boxes and a series of springs arranged longitudinally of the frame, the intermediate portions of said springs supporting said frame and the ends of said springs being supported by the sides of adjacent journal boxes.

20. In a railway vehicle, a frame, a plurality of axles, an equalizing system including journal boxes carried by said axles and having a main body portion arranged to tilt on said axles in a plane extending longitudinally of said frame, said system including a series of springs arranged longitudinally of the frame, the intermediate portions of said springs supporting said frame at the intermediate points of said series, the ends of said springs being suspended from adjacent journal boxes.

21. In a railway locomotive, spaced axles, and articulated equalizing members including journal boxes and a spring extending between said boxes and below the level of the tops thereof, and a side frame extending substantially wholly above said equalizing members and supported by said spring.

22. In a railway vehicle, a frame with depending pedestal jaws, an axle, an axle box including a bearing portion supported on said axle and arranged to tilt about the same, an arm projecting from each side of said bearing portion and forming therewith an equalizer element, and a pair of shoes engaging said bearing portion and slidably engaging adjacent pedestal jaws.

23. In a railway vehicle, a frame with depending pedestal jaws, an axle, an axle box including a bearing portion supported on said axle and arranged to tilt about the same, a pair of spaced arms projecting from each side of said bearing portion and forming therewith an equalizer element, said arms straddling adjacent pedestal jaws, and a pair

of shoes engaging said bearing portion and slidably engaging adjacent pedestal jaws, each of said shoes being located between adjacent pairs of arms.

24. In a railway vehicle, a frame with depending pedestal jaws, axle box elements slideable on said pedestal jaws, a box body journaled in said elements to rotate about the body axis, and an arm projecting from each side of said body portion beyond said pedestal jaws, at least one of said arms providing a support for a spring to support said frame.

25. In a railway vehicle, a frame with depending pedestal jaws, axle box body elements slideable on said pedestal jaws, a box body journaled in said elements to rotate about the box axis, and an arm projecting from each side of said box body and forming therewith an equalizer element.

26. As a new article of manufacture, an equalizer for a railway vehicle including the main body portion of a journal box, said journal box being located at the fulcrum point of the equalizer and transversely spaced arms extending outwardly from each side of the box.

27. As a new article of manufacture, an equalizer for a railway vehicle having the main body portion of a journal box formed as a part thereof, said body portion having a cylindrical outside surface extending transversely of said equalizer and located at the fulcrum point thereof.

28. As a new article of manufacture, an equalizer for a railway vehicle having the main body portion of a journal box formed as a part thereof, said body portion having a cylindrical outside surface extending transversely of said equalizer and located at the fulcrum point thereof, said body portion being open from the bottom for accommodation of an axle journal, and a removable spacer between the lower portion of the sides of said opening.

In testimony whereof I hereunto affix my signature this 17 day of December, 1929.

JAS. C. TRAVILLA, JR.
